UNITED STATES PATENT OFFICE

RICHARD M. DUGDALE, OF DEDHAM, MASSACHUSETTS, ASSIGNOR TO FARRINGTON MANUFACTURING COMPANY, OF BOSTON, MASSACHUSETTS, A CORPORATION OF MASSACHUSETTS

JEWELRY BOX

Application filed January 31, 1929. Serial No. 336,599.

This invention relates to jewelry boxes of the type having legs at the corners and has for its object a construction which permits facile and economical methods of construction, which is substantial and durable in use, which permits the use of sheet metal by stamping and punching processes and which, at the same time, presents a very attractive appearance comparable with costly boxes as heretofore made by hand or otherwise.

For the purpose of illustrating the genus of the invention a concrete embodiment is shown in the accompanying drawings, in which:

Fig. 1 is an end elevation with the cover raised;

Fig. 2 is a top plan of the bottom on the line 2—2 of Fig. 1;

Fig. 3 is a perspective view of a leg stamping;

Fig. 4 is an end view of the stamping after the first bending operation;

Fig. 5 is a developed view of the covering sheet material for each of the legs;

Fig. 6 is an inside view of the stamping in the condition shown in Fig. 4 after the sheet covering has been partially applied;

Fig. 7 is a similar view after the covering has been completely applied;

Fig. 8 is an outside view of the leg after it has been completely shaped and covered ready for application to the box;

Fig. 9 is a section on line 9—9 of Fig. 8;

Fig. 10 is a section on line 10—10 of Fig. 9; and

Fig. 11 is a section on line 11—11 of Fig. 2.

The particular embodiment of the invention chosen for the purpose of illustration comprises a cover C of any suitable construction hinged to the bottom B, the body of which is formed of a metal sheet 1 having its margins bent upwardly to form ends 2 and sides 3. The bottom may be covered by suitable lining material as shown at 4 in Fig. 2 and for most of its intended uses it would also be provided with a jewelry supporting pad fitting in between the ends 2 and sides 3.

According to the particular application of the invention illustrated in the drawings the bottom 1 is provided at each corner with a pair of slots 5, the slots of each pair being angularly related to each other (right angles in the illustration). Each leg is preferably formed by stamping a blank of sheet material in the form shown in Fig. 3 comprising a body of supporting portion 6 and upper extensions or tongues 7 for interlocking engagement with the slots 5. While the surface 8 between the extensions 7 may be relied upon as a shoulder to seat against the bottom of the box, as shown in Figs. 4, 10 and 11 the extensions 7 are preferably bent transversely to provide seating shoulders 9 so that the legs will seat against the under side of the box throughout the entire transverse dimension thereof.

Before each leg is applied to the box it is preferably covered with leather, fabric or other sheet material matching or contrasting with similar material applied to the bottom, as shown at 10 in Fig. 11. The preferred method of applying the sheet covering on each of the legs consists in cutting a blank in the shape shown in Fig. 5 having a central section 5 and extensions 12, 13 and 14. In cementing the covering material on the leg the central section 5 is first applied to the outer surface of the body portion 6 of the leg and the extensions 12, 13 and 14 are then folded over the edges of the leg as illustrated in Figs. 6 and 7.

After the covering material has been applied and the cement has partially or wholly dried the leg is bent horizontally into the form shown in Figs. 8 and 9 so that the extensions 7 are angularly related to each other in the same way as the slots 5. The extensions 7 are then inserted through the slots 5 and bent over as shown in Figs. 2 and 11, thereby affording a construction which is not only rigid and durable but which presents a very attractive external appearance, particularly if the covering on the legs presents a harmonious contrast with the covering material on the body of the box. While the covering material is preferably extended upwardly only to an extent which will permit 100

its upper edge 15 to be pinched little if any between the bottom of the box and the shoulders 8 and 9, it may be extended over the shoulders a distance sufficient firmly to clamp the upper edge 15. By this construction the legs may be covered neatly with little danger of the covering material wrinkling or marring in the process of application and with substantially no likelihood of the covering material peeling off in use.

16 The resulting product is characterized by a polygonal bottom having at the corners sheet metal legs bent horizontally so that their lateral margins extend longitudinally of the 15 sides of the box on opposite sides of each corner.

I claim:

1. A jewelry box comprising a bottom having perforations therein, legs having shoulders seating against the under side of said bottom and means extending through said 20 perforations for securing the legs to the bottom.

2. A jewelry box comprising a bottom having perforations therein, and sheet metal legs having surfaces seating against the under side of the bottom and integral extensions extending through said perforations and overlapping the upper surface of the bottom to interlock the legs with the bottom.

3. A jewelry box comprising a bottom having perforations therein, and sheet metal legs bent to provide shoulders seating against the under side of the bottom, thence extending upwardly through said perforations and thence overlapping the upper surface of the bottom to interlock the legs with the bottom.

4. A jewelry box comprising a bottom having pairs of slots and legs each having a pair of tongues extending through one pair of slots and overlapping the upper surface of the bottom to interlock the legs with the bottom.

5. A jewelry box comprising a bottom having 45 pairs of slots, the slots of each pair angularly related to each other, and legs each having a pair of tongues similarly related and extending through one pair of slots and overlapping the upper surface of the bottom to interlock the legs with the bottom.

6. A jewelry box comprising a bottom and sheet metal legs each having upper extensions in spaced relationship, the legs being bent horizontally between the extensions and the extensions projecting through the bottom and then bending over to interlock the legs with the bottom.

7. A jewelry box comprising a bottom having pairs of slots, the slots of each pair being angularly related to each other, and sheet metal legs each having upper integral extensions, each leg being bent horizontally between the extensions to position the extensions in the same angular relationship as said slots, and the extensions projecting through the

bottom and then bending over to interlock the legs with the bottom.

8. A jewelry box comprising a bottom having pairs of slots, the slots of each pair being angularly related to each other, and sheet metal legs each bent to provide a transverse surface seating against the under side of the box and each having upper integral extensions, each leg being bent horizontally between the extensions to position the extensions in the same angular relationship as said slots, and the extensions projecting through the bottom and then bending over to interlock the legs with the bottom.

9. A jewelry box comprising a bottom having pairs of slots, the slots of each pair being angularly related to each other, and sheet metal legs each having integral extensions first bent transversely to provide shoulders seating against the under side of the bottom and then bent upwardly, each leg being bent horizontally between the extensions to position the extensions in the same angular relationship as said slots, and the extensions projecting through the bottom and then bending over to interlock the legs with the bottom.

10. A jewelry box comprising a sheet metal bottom having slots near the periphery at spaced locations around the periphery and legs provided with flexible tongues extending through said slots for attaching the legs to the bottom, the legs having shoulders seating against the outer surface of said bottom.

11. A jewelry box comprising a bottom part, sheet material applied to the outer surface of said part, and legs mounted on said part, the legs having shoulders presented to the outside of the bottom part and said material extending between said part and legs with said shoulders clamping said material to said part.

12. A jewelry box comprising a bottom part, sheet material applied to the outer surface of said part, legs mounted on said part with shoulders presented to the outside of the bottom part, and other sheet material covering the legs, certain of said sheet material being pinched between said shoulders and said bottom part.

Signed by me at Boston, Massachusetts, this 28th day of January, 1929.

RICHARD M. DUGDALE.
